UNITED STATES PATENT OFFICE.

EMMER F. GWYNN AND HARRY H. JAMES, OF PITTSBURGH, PENNSYLVANIA.

MOTOR-REVERSE CONTROL.

Application filed May 12, 1921. Serial No. 468,989.

To all whom it may concern:

Be it known that we, EMMER F. GWYNN and HARRY H. JAMES, citizens of the United States, and residents of Pittsburgh, in the county of Allegheny and State of Pennsylvania, have invented a new and useful Improvement in Motor-Reverse Controls; and we do hereby declare the following to be a full, clear, and exact description thereof.

10 Our invention relates to a motor reverse control.

In an application of even date herewith, Serial No. 468,988, we have illustrated and described a motor reverse control in which

15 magnets were interposed in the motor circuit between the reversing switches and the motor, the arrangement being such that when the motor is running in either direction one of said magnets will be withdrawn 20 from its contact, and as long as the motor is running in this direction contact will be broken so that in case the lever is suddenly thrown to reverse the magnet will not be released to engage its contact until the motor

25 comes to rest, thereby preventing the blowing out of fuses, stoppage of the elevator at points between the floors, burning out of the motor armature, etc., all of which cause aggravating delays and expensive repairs.

30 The object of our present invention is to effect the same result, but instead of operating the device entirely electrically, as in the application above referred to, the operation is done electro-mechanically.

35 In the accompanying drawings Fig. 1 is a plan view of our improved reverse control, the illustration being largely diagrammatic; Fig. 2 is a view of one of the reversing switches; and Figs. 3 and 4 show modified 40 forms of our invention.

In the drawing the numeral 2 designates an ordinary control-box provided with the lever 3 and the ordinary segmental contact 4.

45 The control-box 2 has the ordinary contacts 5 and 6. The wire 7 leads from the contact 5 to the electro-magnet 8 with the longitudinally movable core-bar 9 which also enters the magnet 10. On the core-bar 9 is the collar or stop 11. Springs 9^a are 50 provided to return the core-bar to normal position.

Projecting out from the core-bar 9 are the brackets 12 and 13 having contacts 13^a and 14^a which normally engage the pins 14 and 15, respectively, said pins having the

heads 16 which fit within the small cylinders 17, and springs 18 are interposed between the ends of said cylinders and the heads of said pins acting to normally force said pins outwardly.

60 The electro-magnet 19 has the core 20, the outer end of said core engaging the lever 21 which is pivoted at 22 on the arm 23 on said electro-magnet 19. A spring 24 surrounds the core 20 and acts normally to hold the 65 lever 21 in the full line position shown in Fig. 1. The electro-magnet 19 is connected up to the circuit of the motor 25.

Suitable reversing switches 26 and 27 are provided, the construction of said switches 70 being more specifically illustrated in Fig. 2.

75 It has not been deemed necessary to refer to the circuit in detail, as that is a matter which is well understood by those skilled in the art, and is the ordinary circuit employed in the operation of electric elevators, although it will be clearly understood that we do not limit our invention in any way to this application of our invention.

The operation is as follows:

80 Energizing magnet 27^a pulls down reversing switch for forming a circuit for the motor in which current flow from the main line will be through fuse 30, lead 31, contact 27^a of the reversing switch (not shown) 85 through the switch to lead 32, contact 33, lead 34, contact 35, and then to the reversing switch for forming a circuit to drive the motor in the opposite direction of rotation (said switch not shown), through said 90 switch to contact 36, lead 37, solenoid 19 and lead 38 to the motor 25, thence by lead 39 to contact 40 through said first mentioned reversing switch to contact 41, lead 42, contact 43, said last mentioned reversing switch, 95 contact 44, lead 45 and to the motor resistance 46, then back to opposite side of the line by lead 47.

100 Reversing the control handle 3 energizes magnet 27^b, pulling down reversing switch for completing a circuit to drive the motor in the opposite direction. Current flow from the main line A will then be through fuse 30', lead 48, contact 48^a, reversing switch, lead 49, contact 35, lead 34, contact 33, to said first mentioned reversing switch 105 to contact 50, lead 51, to contact 43, lead 42 to the switch operated by magnet 27^a to contact 53, lead 39 to the motor 25, thence by lead 38, solenoid 19 and leads 37 and 37^a 110

to contact 54, said first switch and contact 55, to lead 45 and to motor resistance 46, then back to line by lead 47.

The motor then proceeds in the reverse direction, but only after it has been permitted to come to rest, and the annoyance and inconvenience due to blowing out of fuses, stoppage of the elevator at points between the floors, burning out of the motor armature, etc., are all practically obviated.

In Figs. 3 and 4 we have illustrated a modified form of our invention in which the electro-magnets 28 and 29 are interposed between the reversing switches 26 and 27 and control-box. The cores 30 and 31 of the electro-magnets 28 and 29 are connected to the lever 32 which is pivoted at 33 to the bracket 34. The lever 32 has the projecting arm 35 carrying the contacts 36 and 37 which are adapted to engage the pins 38 and 39 adapted to move back and forth in the cylinders 40, the springs 41 being provided for normally advancing said pins into engagement with the contacts 36 and 37 when the operating lever is at neutral position.

The vertically movable rod 42 is connected to the arm 35, said rod having a telescopic connection with the shaft 43. The vertical shaft 43 has the governor mounted thereon consisting of the bracket 44 with the arms 45 pivotally connected thereto and carrying at the lower ends the weights 46. The upper ends of the arms 45 are turned inwardly, as at 47.

The rod 42 is provided with the collar or abutment 48. The shaft 43 may be driven in any suitable manner from the motor directly or indirectly, the shaft 49 being connected by means of the bevel gears 50 and 51.

The operation is as follows:

When the operating lever is at neutral position the parts will have the positions indicated in Fig. 2, but if the operator 45 throws the lever so as to bring the segmental contact 4 into engagement with the contact point 5 the electromagnet 28 will be energized and the core 30 drawn inwardly, the parts assuming the positions indicated 50 in Fig. 3 where the lever 32 is moved so that the arm 35 draws the contact 37 from pin 39 while the contact 36 is moved upwardly, compressing the spring 41. The movement of the operating lever through the reversing switch 26 will start the motor and with the operation of the motor the governor is put in operation, and the centrifugal action of the arms 45 will throw the inwardly projecting ends 47 inwardly so 55 as to be below the stop or abutment 48 on the rod 42 which has been raised by the movement of the lever 32. As long as the motor continues to run the rod 42 will be prevented from moving downwardly and 60 the separation between the contact 37 and

the pin 39 will be maintained so that in case the operator should suddenly throw the lever into reverse by bringing the segmental contact 4 into engagement with the contact point 6, such movement will have no effect 70 to reverse the motor, for as long as the inwardly projecting ends 47 of the arms 45 of the governor are below the abutment 48 the contact 37 cannot move into engagement with the pin 39. When, however, the motor finally comes to rest the governor will assume the position indicated in full lines, Fig. 3, and this will permit the rod 42 to descend, to permit the contact 37 to engage the pin 39, and the inward movement of the 80 core 31 of the electro-magnet will force the pin 39 downwardly and will break the contact between the contact 36 and the pin 38. In this manner the reversal of the motor will be effected and without the difficulties 85 above enumerated.

What we claim is:

1. In a motor reverse control, the combination with the control-box and lever, of reversing switches, magnets interposed between said switches and the control-box, a longitudinally movable rod operated by said magnets, contacts connected to said rod for opening and closing the circuit to said switches, and means operated by the motor 95 for preventing the return movement of said rod until the motor comes to rest.

2. In a motor reverse control, the combination with the control-box and lever, of reversing switches, magnets interposed between said switches and the control-box, a longitudinally movable rod operated by said magnets, contacts connected to said rod for opening and closing the circuit to said switches, an abutment on said rod, and means operated by the motor moving into the path of said abutment for preventing the return movement of said rod until the motor comes to rest.

3. In a motor reverse control, the combination with a control-box and lever, of reversing switches, magnets interposed between said switches and the control-box, a longitudinally movable rod operated by said magnets, contacts connected to said rod for opening and closing the circuit to said switches, an abutment on said rod, and a member movable into the path of said abutment operated by said motor and automatically withdrawable when said motor is at 120 rest.

4. In a motor reverse control, the combination with the control-box and lever, of reversing switches, magnets interposed between said switches and the control-box, a longitudinally movable rod operated by said magnets, contacts connected to said rod for opening and closing the circuit to said switches, an abutment on said rod, and a governor comprising pivotally mounted 125

weighted arms, and connections between the motor and said governor for rotating same.

5. In a motor reverse control, the combination with the control-box and lever, of reversing switches, magnets interposed between said switches and the control-box, a longitudinally movable rod operated by said magnets, contacts connected to said rod for opening and closing the circuit of said switches, an abutment on said rod, a governor comprising pivotally mounted weight-

ed arms having inwardly extending end portions, and connections between said motor and said governor for rotating same.

In testimony whereof we, the said EMMER 15 F. GWYNN and HARRY H. JAMES, have hereunto set our hands.

EMMER F. GWYNN.
HARRY H. JAMES.
